CLAIM

The ornamental design for a battery pack, as shown and described.

DESCRIPTION

FIG. 1 is a front isometric views of a battery pack of our new design.

FIG. 2 is a rear isometric view thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof.

FIG. 8 is a bottom plan view thereof; and,

FIG. 9 is a sectional view taken along line 9-9 of FIG. 4. The broken lines in the drawings are for the purpose of illustrating portions of the battery pack that form no part of the claimed design.

1 Claim, 9 Drawing Sheets(56)
